UNITED STATES PATENT OFFICE.

FRIEDRICH ZINZEN, OF DÜSSELDORF, GERMANY.

DRILLING-MACHINE.

SPECIFICATION forming part of Letters Patent No. 544,495, dated August 13, 1895.

Application filed June 30, 1894. Serial No. 516,198. (No model.)

To all whom it may concern:

Be it known that I, FRIEDRICH ZINZEN, a subject of the German Emperor, residing at Düsseldorf, Germany, have invented certain new and useful Improvements in Boring-Machines, with description as follows.

This invention relates to a boring-machine, and more particularly to the means for radially adjusting a series of spindle-carriers upon the spindle-head.

In the accompanying drawings, Figure 1 is a sectional elevation of the machine; Fig. 2, a cross-section on line xx , Fig. 1; and Fig. 3, a vertical section on line yy , Fig. 1.

15 The letter A represents the frame of the machine, which is provided with the jointed boring-shafts B, that receive their rotary motion from the work-shaft in suitable manner. To the lower ends of the shafts B there are 20 coupled the angular spindle-carriers f, having a horizontal and a vertical arm.

25 g is a ring which contains a circular groove n in its upper face, adapted for the reception of screws d , that serve to attach the spindle-carriers to the ring. The upright arms of the spindle-carriers receive the boring-spindles, while the flat horizontal arms are provided with long slots t , through which the screws d pass.

30 In order to permit the spindles to be set nearer to or farther away from the center of the spindle-head, each of the slots t contains a horizontal screw d' , which passes with its thread through the screw d . The ring g is divided by a series of radial grooves n' , while 35 similar grooves n^2 are formed in the lower face of the carriers f. If the grooves $n' n^2$

are brought into alignment and connected by a common feather s , an accurate radial guide for the boring-spindles is obtained.

In order to set the carriers to the exact diameter of the circle desired, each spindle-carrier is provided with a scale m , operating in conjunction with a circular mark q , that constitutes the pointer. The radial guidance of the spindle-carriers may be accomplished in 45 different manner, if desired.

I disclaim in a multiple drill the combination, with the drill-carrying spindles and flexible shafts for driving the same, of an open frame and inwardly-projecting bracket-supports for the drill-carrying spindles, adjustably connected with said frame.

What I claim is—

1. The combination of a series of angular grooved spindle carriers with a ring having a 55 circular groove and a set of radial grooves and with screws d engaging the circular groove, and feathers s , engaging the radial grooves, substantially as specified.

2. The combination of ring g having circular groove n , and radial grooves n' , with angular spindle carriers f , connecting screws d , set screws d' , and feathers s , substantially as specified.

In testimony whereof I have signed this 65 specification in the presence of two subscribing witnesses.

FRIEDRICH ZINZEN.
